UNITED STATES PATENT OFFICE

2,512,320

VALVE

Frederick C. Fischer, Edgar, Wis.

Application February 5, 1946, Serial No. 645,580

2 Claims. (Cl. 251—164)

1

The present invention relates to valves and is more particularly concerned with a manually operated valve to be interposed in a water or gas conduit and the like.

The primary object of the invention is to provide a device of the character referred to which is simple to construct and contains few cast elements.

Another object of the invention is to provide a valve which will be durable when used in a water conduit.

A further object of the invention is to provide a valve which can be readily installed and is of simpler and more compact construction than prior devices.

With the foregoing and other objects and advantages in view, the invention consists of the novel construction and arrangement of parts hereinafter described and claimed.

In the accompanying drawing illustrating the invention:

Figure 1 is a longitudinal section of the invention.

Figure 2 is an end elevation thereof.

Figure 3 is a top plan view.

Like numerals are used in the description and drawing to designate the same parts of construction.

1 is the valve case which is preferably a section of pipe or a cylindrical body 2 having enlarged or flared ends 3, threaded interiorly, as at 4, for pipe coupling purposes. Externally the flared ends are formed with facets or wrench surfaces 5 to facilitate connection of the valve case and the threaded ends of pipes serving as conduits for water, gas and the like.

A cylindrical chamber 6 is formed longitudinally in said case and extends from end to end, approximately. This chamber serves as a valve cylinder for a cylindrical valve 7 and is provided with a port 8. A baffle 2—a is located inside case 1 adjacent its outlet and between same and said port to divert the flow into the port. The inner wall of the baffle is curved to facilitate the passage of water or gas without agitating it. Chamber 6 has an open end which projects through the baffle. The cylindrical valve 7 and the interior wall of valve cylinder 6 are both highly polished with a finish similar to that common to pistons and cylinders of motor cars and the like. To this end, the cylinder 6 is bored and polished as in the case of combustion engine blocks. The length of the valve approximates the distance from the port 8 to the closed end 9 of the valve cylinder. The opposite or open

2

end 10, of same, provides the outlet or passageway from the valve case proper, through the port 8. The valve is manually operated by means of a laterally disposed rod or bolt 11, threaded therein at a suitable distance from its innermost end, and projecting outside the valve case through a longitudinal slot 12 in the body thereof. By sliding the bolt 11 as desired, the valve can be moved in either direction as much as required for either a full or partial opening of port 8, thus regulating the volume of flow.

The projecting portion of the bolt is contained in a lock member 13, which is provided with an open, cylindrical bore 14 designed to hold an helical spring 15. The spring is confined between an annular shoulder near the bottom of the lock member and a shoulder underneath the head 16 of bolt 11.

The foot of the lock element 13 is cross cut to form two jaws 17 which are designed to normally engage the notches or spaces formed by parallel ribs 18 on the outer surface of the case 1 adjacent the slot 12. These ribs are disposed transversely of the case, thus forming a rack bar 25 along which the lock member may be moved, when lifted, and secured when lowered. This construction facilitates longitudinal adjustment of the piston within the limits of slot 12. To permit the lifting of the lock member, it is provided at the top with a flanged enlargement 19, within which is an annular recess 20 which allows reciprocatory movement of the lock member on bolt 11 and its head. By placing one's fingers under the flange on the lock member and thumb on head of bolt, the member can be lifted out of engagement with the said notches. When moved to a new or adjusted position, the lock member is lowered into engagement with the notches, thus securely locking the piston in the desired position.

The lock member is preferably stamped while the casing 1 and piston block are cast as a unit and then bored for the valve cylinder 6. As this valve is moved infrequently in the case of a water conduit, the wear is infinitely less than that on the piston and cylinder of a combustion engine, thus reducing the possibility of a leak to a minimum. This will obviate frequent replacement of parts as in most valves. When wear warrants regrinding of the cylinder 6 it may be done readily through the open end thereof.

Having thus described my invention what I claim as new and desire to secure by Letters Patent, is:

1. A valve comprising a section of pipe

threaded at each end for coupling purposes and provided interiorly with a baffle, an ancillary cylindrical chamber located within said section of pipe and provided with an open end extending through the baffle, a port in the longitudinal wall of said chamber adjacent the inner surface of the baffle, a slideable piston-like valve in said chamber, positioned to serve as a closure for said port, means secured to said valve and extending exteriorly of the valve case through a longitudinal slot therein for operating said valve, and an adjustable member attached to said valve operating means for locking same in various positions in said slot.

2. A valve comprising a case having interiorly threaded annular ends, a baffle in said case provided with a curved inner wall, an integral ancillary valve cylinder positioned longitudinally within said case and provided with an open end extending through the baffle, a communicating port between the ancillary valve chamber and the main chamber of the case and adjacent the

inner surface of the baffle, a slideable piston-like valve in said valve chamber positioned to serve as a closure for said port, a longitudinal slot between said ancillary chamber and the exterior of said case, a removable bolt secured to said valve and projecting exteriorly of the case through said slot, a plurality of recesses on the exterior of the case contiguous to said slot, and a spring-controlled reciprocatory locking member mounted on said bolt and provided with an element to engage said recesses.

FREDERICK C. FISCHER.
